UNITED STATES PATENT OFFICE.

CHARLES EBEL, OF NEW YORK, N. Y., ASSIGNOR TO HIMSELF AND HENRY SIMERMAYER, OF SAME PLACE.

HYDRANT.

SPECIFICATION forming part of Letters Patent No. 247,895, dated October 4, 1881.

Application filed March 9, 1881. (Model.)

To all whom it may concern:

Be it known that I, CHARLES EBEL, of the city, county, and State of New York, have invented a new and useful Improvement in Hydrants; of which the following is a specification.

The invention consists in connecting the nozzle-pipe of a hydrant with a sewer, so that it may be emptied in cold weather by the means hereinafter described, and pointed out in the claims.

The object of this invention is to prevent hydrants from freezing.

The drawing represents a sectional side elevation of the improved hydrant.

In the drawing, A represents the hydrant, of which B is the nozzle and C the hydrant-casing. D represents the water-main to which the hydrant A is attached.

E represents the water-chamber of the hydrant A, from the outside of which a cylindrical shell, F, extends upward, inclosing the stuffing-box G and gland G', through which the valve-stem H is entered perpendicularly.

I" represents the hydrant-cover, designed to be on a level with the sidewalk.

The valve-stem H is screw-threaded, as shown at a, where it passes through the corresponding screw-threaded lower portion of the stuffing box G, and said valve-stem H carries fixed upon it a valve, I, that fits into a corresponding valve-seat, I', formed in the bottom of the water-chamber E, which chamber E communicates directly with the water-main D.

On the lower end of the valve-stem H, which extends down through the passage K into the waste-chamber L, is another valve, M, that is designed to fit into a corresponding valve-seat, M', in the top of said waste-chamber L, so that when the upper valve, I, is opened the lower valve, M, closes and the flow of water is from the main D, through chamber E, passage K, and nozzle B, and when the valve I is closed the valve M is opened, and the flow of

water through the hydrant is cut off, and what water remains in the nozzle B escapes

through the valve-opening M' into the waste-chamber L, and thence through the waste-pipe O into the sewer P, so that there will be no water left in the nozzle B to freeze in cold weather, while the water-chamber E is designed to be so far below the surface of the street that the frost will not reach it; hence said hydrant A will always be ready for use.

In warm weather, when it is not necessary to empty the nozzle B to prevent its freezing, the valve Q in the waste-pipe O may be closed, thereby preventing escape of water from the chamber L, the bottom of said waste-chamber L being closed by the screw-cap L'. Said valve Q may be regulated by a rod, R, extending upward in the shell F within convenient reach of the operator.

This hydrant is simple and cheap in construction, its water and waste chambers and intermediate passages, with their valve-seats and cylindrical shell, being all comprised in one casting.

Having thus described my invention, I claim as new and desire to secure by Letters Patent—

1. The combination, with the nozzle-pipe B, the water-chamber E, and the passage K under the water-chamber, of the stem H, screwing into stuffing-box G, and carrying valves I M, fitting seats I' M', as shown and described, whereby the nozzle-pipe may be emptied in freezing weather by simply screwing down the stem to seat valve I and unseat valve M, as set forth.

2. In a hydrant, the combination, with the nozzle B, passage K, and waste-chamber L, of the waste-pipe O, provided with valve Q, substantially as and for the purpose described.

3. In a hydrant, the combination, with the passage K, of the waste-chamber L, provided with valve-opening M', cap L', and waste-pipe O, substantially as herein shown and described.

CHARLES EBEL.
